UNITED STATES PATENT OFFICE

2,378,903

GRINDING MACHINE

William G. Baldenhofer, Springfield, Ohio, assignor to The Thompson Grinder Company, Springfield, Ohio, a corporation of Ohio

Application September 19, 1941, Serial No. 411,529

22 Claims. (Cl. 51—92)

This invention relates to improvements in surface grinding machines, it more particularly relating to improving a grinding machine of the type shown and described in my Patent No. 2,068,529, dated January 19, 1937, having a tool-head slidably mounted on a vertically disposed column, the tool-head carrying a grinding wheel and being capable of making successive intermittent traversing feeding movements across a work-piece carried on a reciprocating work-holder, in which machine in grinding the tool-head is lowered manually to grind stock from the work-piece, whereby certain manual operations of that patent are automatically performed.

In the present application, a machine such as that of said patent may be considered as one form of a construction to which the invention in any or all of its parts may be added to the end that the convenience and advantages in operation of the machine of that patent are augmented. The invention tends toward a much greater ease of operation in that the grinding cycle is practically automatic in character, whereby acceptable work is produced by operators of limited experience. The fore part of the following specifications up to the point of bringing in the new added elements is similar to the description found in the patent mentioned, and the reference characters employed in this fore part are, as far as possible, the same as those used in the abovementioned patent for equivalent elements.

Before setting out the objects and advantages of the present invention, a brief explanation will be made of the manner in which the machine of the patent is operated. With this machine, a work-piece is placed in position, the height of the grinding wheel is adjusted, the control reverse dogs are adjusted, the reciprocations of the work-table and the cross-feeding of the tool-head are started, while the operator manually lowers the grinding wheel from time to time as the wheel removes stock from the work-piece. When the surface is finished, the grinding wheel is manually elevated to the former height, and a new work-piece is loaded in position. To lessen the hazard to the operator, re-loading is preferably made with the work-holder removed to a point remote from the grinding wheel, which is seldom shut down once it has been started, and if arrangements were made in the machine of the patent for a loading position, it is usually the case that the work-holder is moved to this position only by the manual shifting or changing of some of the control elements such as work-holder

reversing dogs. After re-loading, the work-holder must again be manually returned to the vicinity of the grinding wheel and the control elements readjusted for the normal grinding stroke.

In the machine of the present application devices are provided by means of which the above-mentioned steps are carried out automatically. The new machine may, therefore, be considered as extending the conveniences and advantages of the machine of the patent referred to.

One of the objects of the present invention is to provide that in the automatic grinding cycle when started the grinding wheel is automatically lowered in what is known as the down-feeding portion of the cycle. The total amount of down-feeding is variable by adjustment to suit different working conditions, with a provision for adjustably securing a variation in the extent of an individual down-feeding increment. The down-feeding is maintained at these set regular increments until the desired low point the tool-head is to reach is attained, when further down-feeding is arrested.

Another object is the provision of mechanism whereby a part of the automatic grinding cycle known as the smoothing or "spark-out" period follows in rotation when down-feeding is arrested. This "spark-out" period is a surfacing operation continued for a regulatable length of time with the tool-head held at the low point it reached when down-feeding ceased. This operation is advantageous since the surfaces of the work-pieces are often uneven, and as is usual in surfacing machines, the grinding wheel follows the irregularities to a limited extent. In sparking-out, the decrease in the volume of sparks coming from a stationarily held wheel (so far as elevation is concerned) shows that only the high points are being ground away without proportionate increase in the depths of adjacent lower portions. The duration of time allowed for the spark-out period is easily varied in the present machine by a simple adjustment.

Another object is to provide means whereby when the work-holder reaches the loading position, the tool-head is automatically elevated to its former height, this elevation being made with a degree of exactness such that in mass production schedules, where the raw material is of relatively uniform thicknesses, it is possible to start the next grinding cycle on the next work-piece with no adjustments other than such as are necessary to compensate for the natural wearing down of the grinding wheel.

However, it should be explained that another object is to provide that with the work-holder moved onto the loading position, this member is retained in this position for the length of time the operator may desire, and that to re-start the machine on a succeeding automatic grinding cycle, the operator has only to open a push-button switch.

Another object is to provide means whereby, should it be preferred that the present machine be operated as the simpler type of the aforementioned patent, which may be advisable when work-pieces differing in character are routed to the machine, such operation is obtainable by the opening of a switch in the electro-hydraulic control system of the present machine.

Other objects will appear from the accompanying specification and claims.

In the accompanying drawings:

Fig. 1 is a front elevation of a machine embodying the improvements.

Fig. 2 is a view partly in side elevation and partly in longitudinal section, on a larger scale than Fig. 1, the sectional portions being taken on the line 2—2 of Fig. 1.

Fig. 3 is an enlarged fragmentary horizontal section on the line 3—3 of Fig. 2.

Fig. 4 is an enlarged fragmentary elevation of a portion of the invention, i. e., a switch actuating mechanism seen in elevation in Fig. 1.

Fig. 5 is an enlarged vertical section on the line 5—5 of Fig. 2.

Fig. 6 is a fragmentary view similar to Fig. 5 but with some of the parts of that figure shown in a different working position.

Fig. 7 is a fragmentary horizontal section on the line 7—7 of Fig. 5.

Fig. 8 is a diagrammatic showing of the devices by which the novel features of the invention are obtained, together with a showing of the hydraulic and electric circuits pertaining to the invention, with some of the parts being shown in longitudinal section and other parts in elevation.

Fig. 9 is an enlarged detail showing a modification of the means for arresting the down-feed of the tool-support, the view being a front elevation of a portion of the hand wheel, partly broken away which is associated with the mechanism which operates the tool slide, and of parts associated therewith which control the extent of the down-feed of the tool-support.

Fig. 10 is a top plan of Fig. 9 with some of the parts shown in longitudinal section, some of the sectional parts being on the line 10—10 of Fig. 9.

Fig. 11 is a detail view partly in side elevation and partly in longitudinal section showing in full and dotted lines three different positions of the switch operating lever.

Fig. 12 is a front elevation of a detail to show some of the parts in a different position than that illustrated in Fig. 9.

Fig. 13 is a diagrammatic view of the switch and its circuits and the parts which operate the switch, some of the parts being broken away.

Referring to the drawings, the base of the grinding machine is indicated at 1. On this is mounted for reciprocatory motion on a V-way 2 and a flat-way 3 a work-holder 4 to which the work W may be attached by any of the usual methods.

Reciprocatory motion is imparted to the work-holder by means of fluid pressure acting in a fluid motor. This motor comprises a cylinder 5, one end of which is secured to the inside upper

portion of the base 1 (Fig. 1), a piston 6 (Fig. 8) and a piston rod 7, the outer end of which is secured to a downwardly-extending arm 8 attached to an extension of the work-holder 4 (Fig. 1). Fluid under pressure is admitted alternately to each end of the cylinder 5, there being a port 9 at the right, and a port 10 at the left of the cylinder 5 (left center Fig. 8). Communicating with these ports are conduits 11 and 12, respectively, which lead to ports in the body portion 13 of the unitary structure housing the hydraulic valve control mechanism.

The work-holder is reversed at the ends of a desired stroke by the reciprocatory movements of a master piston valve to which motion is imparted by means of fluid pressure under the control of a piston pilot valve, which in turn receives its motion from the work-holder itself. Due to the small size of the pilot valve and although the pilot valve operates in fluid pressure equal to those pressures which the master valve controls, the movements of the work-holder are not affected.

The pilot valve is moved by contact of stop-dogs 14 and 15 (Figs. 1 and 8), adjustably positioned on the work-holder, with lugs 16 and 17 integrally attached on the forward and rear side of a reversing lever 18, which is pivotally mounted, on the forward side of the base 1, on the shaft 19. The shaft 19 extends into the interior of the base 1 and on its inner end there is secured a forked lever 21, Fig. 8, which straddles the extended stem 23' of the pilot valve 23 between the collars 23" on this stem. The pilot valve 23 is a portion of the hydraulic valve control mechanism which will be described later in the specifications.

The abrasive wheel 24 (Figs. 1 and 2) is mounted on the end of the horizontal shaft or spindle 25 supported in bearings (not shown) carried by the tool-holder or slide 28. The tool-holder is supported in angularly disposed ways 29 machined in the lower part of a projecting portion 30 of a vertical support or slide 31. The support 31 or slide 31 is gibbed by gib 32 to the vertically disposed ways 33' of a column 33 attached to the base 1, and by means of a grinding wheel elevation mechanism may be elevated or lowered so that the position of the wheel 24 with respect to the work on the work-holder 4 may be altered.

The grinding wheel elevating and lowering mechanism comprises an elevating screw 26, Figs. 1 and 2, depending from bearings in the upper end of the column 33. The screw is threaded through a nut 20' secured to the column side of the vertical support or slide 31, and at its lower end there is secured the gear 21 (Fig. 2) meshing with a pinion 21'. The pinion 21' is secured on the inner end of an elevation cross-shaft 22 rotatably carried in bearings in the base. The cross-shaft extends forwardly through the forward wall of the base, and on its outer end is fixed a hand wheel 22'. On the portion of the cross-shaft 22 just outside the base there are attached certain members of the devices by which the automatic elevation and lowering of the grinding wheel is provided, the parts being contained in a housing interposed between the forward wall of the base 1 and the hand wheel 22'. A full description of these new parts will appear in a latter portion of the specification. Rotation of the hand wheel 22' and cross-shaft 22 in an anti-clock-wise direction as viewed in Fig. 1 results in a lowering of the support or slide 31 and of the holder 28 and grinding wheel carried there-

by, while the reverse rotation elevates the parts.

The tool-holder or slide 28 is actuated by a fluid motor similar to the motor previously described in connection with the operation of the work-holder. This fluid motor comprises a cylinder 34, one end of which is secured to the inner surface of the rear wall 35 of the vertical support or slide 31. A piston 36 (Fig. 8) on the inner end of a piston rod 37 operates within the cylinder 34, while the outer end of the piston rod 37 is connected to a vertically extending arm 38 secured to the upper portion of the tool-holder or slide 28. Fluid under pressure is admitted in successive charges to either end of the cylinder 34 whereby the slide 28 is moved step-by-step in either direction in a horizontal plane at right angles to the direction of travel of the work-holder 4.

The direction in which the intermittent movements of the tool-holder or slide 28 are made is under the control of a piston type reversing valve indicated at 34' (Fig. 8), and when a desired number of movements is made in one direction, the valve is longitudinally shifted to change the movement to the reverse direction. This valve is contained in a valve housing integrally attached to the tool-holder fluid motor cylinder 34, Fig. 8, and may be manually shifted by means of the forwardly extending stem extension 26 ending in a knob 26' outside the forward wall of the vertical support 31. In the automatic operation of the machine, the valve is shifted by the tool-holder stroke limiting dogs 109 and 109', the dog 109, which limits the rearward movement being shown in Figs. 1, 2 and 8, while the dog 109' which limits the forward motion of the tool-holder is shown in plan in Fig. 8. It is identical with the dog 109 except that it is in reversed-hand form.

These dogs 109 and 109' are adjustably secured to a T-slot bar 109" attached to the tool-holder or slide 28, and effect the reversal of the tool-holder reverse valve through linkage which consists of a rock-shaft 110 rotatably mounted in the vertical support 31, a down-turned lever arm 110' on the outer end of the rock shaft 110 in such position as to project in the path of the dogs 109 and 109' whereby the shaft is rocked, and an up-turned, forked lever 111, Figs. 2 and 8, which straddles the valve extension 26 between a pair of collars 26" secured to this extension. It should be explained that with this type of valve reversing linkage and valve that as the valve passes over center, all fluid pressure that created the movement of the tool-holder or slide is cut off; that is, each dog can move or shift a valve of this type but half its reversing stroke only. To complete the stroke, use is made of a wedge-cam and an over-the-center spring arrangement whereby the remaining portion of the reversing stroke is brought about by the action of a spring. The wedge-cam is secured to the valve extension 26, Figs. 2 and 8, and is indicated at 112, and the spring at 112' (Fig. 8) contained in a housing attached to the cylinder 34. The spring acts through a plunger 113 on one side or the other of the wedge-cam 112, whereby the valve is shifted in a manner well known to those acquainted with this art.

Fluid is conveyed to the cylinder 34 by means of conduit 39, the fluid being admitted to the cylinder through ports 41 and 42 respectively, in the forward and rear ends of the cylinder heads of the cylinder 34 under the control of hydraulic valve control mechanism in a manner later to be described.

The grinding wheel spindle 25 is rotated by means of an electric motor shown conventionally in Fig. 1, 44 representing the field ring and 45 representing the rotor of this motor, the rotor being secured directly to the spindle.

The fluid under pressure is supplied to the hydraulic valve control mechanism by means of a pump 46 driven by a small electric motor (not shown). A conduit 48 connected to the suction side of the pump 46 conveys fluid from a receptacle 49, the suction end of the conduit 48 being submerged below the fluid level of the fluid which is stored in the receptacle. To the discharge side of the pump is connected a pipe 50 which leads to the valve control mechanism 13; interposed in this pipe is a pressure regulating and relief device shown conventionally at 51 whereby the pressure is regulated.

Valve control mechanism

The manner in which the work-holder 4 is started, stopped, automatically reversed at the ends of the desired stroke follows a customary practice. The supply of fluid to either end of the work-holder fluid motor is under the direct control of a master piston valve which itself is under the control of the previously mentioned pilot valve 23 (center, Fig. 8). It is preferable to interpose a stopping, starting and throttling valve 58 between the source of supply of the fluid and the work-holder fluid motor whereby the movements and rate of speed of the work-holder may be controlled independently of the movement of the pilot valve. The advantages of this construction are that the operator may stop the work-holder at any point desired and resume operations in either direction at the same or changed rate of speed. The pilot valve 23 also controls the successive intermittent movements of the tool-head whereby when the work-holder movement is stopped no movement of the tool-head may be made except by a separate control means, there being a distinct advantage in this provision, as in case if the stopping of the work-holder is for the purpose of making measurements on the work, continued motion of the tool-head at this time might be a source of danger to the operator. The master valve is given a reciprocator movement so as to supply fluid to one end and allow the exhaust of the fluid from the other end of the work-holder fluid motor.

Referring to Fig. 8, center portion, the master valve is indicated at 53. It consists of a series of lands or piston portions integrally attached to a cylindrical rod and is closely fitted in a comparatively long bore 57 in the lower portion of the hydraulic valve control body 13. Fluid is fed to the throttle valve 58 from a port 55, thence downwardly through a port 55' which leads directly into the bore 57. The stop and throttle valve 58 of the plug type is horizontally positioned in the valve body 13, intersecting the port 55', whereby the fluid may be entirely cut off and prevented from reaching the master valve 53. A lever 94 is attached to the cylindrical extension 95 of the throttle valve 58 by which this valve is actuated.

Referring to Fig. 8, in the plug type valve 58 a suitable notch 59 is machined in one side of the valve body in alignment with the port 55' so that when the throttle valve 58 is rotated, in the present case through a one-quarter turn, the full capacity of the port 55' is presented for a flow of fluid to the master valve bore 57.

The master valve 53 is a piston valve acting

as a free piston, and is provided at its central portion with the land 60 (Fig. 8). In this view the land 60 is in position to permit a flow of fluid from the port 55' to the conduit 12 leading to the left-hand end of the work-holder motor cylinder 5 with the obvious result that the work-holder will move to the right. As the work-holder moves in this direction, the right end of the cylinder is opened to exhaust by providing that the flow of fluid is reversed through the conduit 11 and is discharged to the storage tank 49 through a port 62 which will be noticed leading directly from the master valve bore into a cored exhaust passage 63 which is positioned in parallel relation to the master valve bore 57. Fluid from the exhaust port 63 is eventually returned through a conduit 64, then through a mechanically operated hydraulic device indicated in general at 253 (right central portion, Fig. 8) designed to reduce work-holder speed as this member is approaching the loading position during the automatic grinding cycle, then through a conduit 64' to the tank 49. A description of the retarding device appears later.

The position of the master valve as shown in Fig. 8 is a result of fluid pressure existing at this time in the extreme left end of the master valve bore 57. This pressure acts against the land 65 of the master valve and therefore moves the valve to the right end of the bore. The fluid which caused the movement is supplied under the control of the pilot valve in the following manner: Fluid pressure from the port 56 enters the pilot valve bore 66 between, at this time, the central enlarged land 70 and left-hand land 71 of the pilot valve. Two ports lead from this portion of the bore; the function of one of these ports 69' being explained hereafter. The other port 72 leads to the left end of the master valve bore 57, while at 81 is shown an exhaust port, at present blocked by the land 71. The fluid flows into the downwardly positioned port 72 into the master valve bore 57 to move the master valve 53 to the right.

So long as the master valve is in this position, fluid will flow into the left end of the work-holder fluid motor cylinder 5 and cause the work-holder to move to the right. When the dog 14 on the work-holder strikes the lug 16, the resulting pivotal movement of the reversing lever 18 moves the pilot valve to the left and as the pilot valve controls the master valve, the master valve is moved to the right, which movement reverses the work-holder movement. The manner in which the master valve is moved to the left is identical with that already described for the master valve movement to the right. In Fig. 8 the pilot valve is at its extreme right hand position, this being the result of a previous work-holder reversal. On the movement of the pilot valve to the left, fluid pressure is diverted from the port 56 to a pair of ports 87 and 88. One of these ports 87 corresponds to the port 69' at the left end of the pilot valve bore, its purpose appearing later. The other port 88 leads downwardly and fluid flowing therethrough flows through an external conduit 243 and eventually arrives at the extreme right end of the master valve bore but in so doing the fluid passes through an electro-hydraulic blocking device 89 (right center, Fig. 8) to be described fully later, and from the blocking device 89 through a second external conduit 245 to the right end of the master valve bore 57. Simultaneously, with the downward flow just described, the fluid at the

extreme left end of the master valve bore displaced by the movement of the master valve is flowing to exhaust in reverse flow through the port 72 into the pilot valve bore. With the pilot valve at its left position as seen in the figure, the ports 89' and 72 are in communication with the exhaust port 81 which leads to the exhaust conduit 64.

Continued movement of the work-holder 4 to the left follows until the dog 15 strikes the lug 17 of the work-holder reverse lever 18. This restores the pilot valve 23 to the right-hand position as seen in Fig. 8, with the results described. This movement also connects the extreme right end of the master valve bore to exhaust, permitting fluid therefrom to flow in reverse order through the conduit 246, the blocking device 89, conduit 243, and port 88 into the pilot valve bore 66 and thence through the downwardly extending port 81' which communicates with the previously mentioned exhaust port 81, and thence to the main exhaust conduit 64.

Tool-holder motor

The motor which operates the tool-holder receives a regulated quantity of fluid at each reversal of the work-holder and is supplied with fluid from the same source as the work-holder motor. This is accomplished by providing an admission valve for the tool-holder motor which is operated by the fluid and at a speed in proportion to the pressure of the fluid so that upon a lower pressure a longer time interval is allowed to admit the fluid to the tool-holder motor, while at a greater pressure of the fluid a shorter time interval is allowed to admit the fluid to the tool-holder motor, thus insuring the admission of a substantially uniform quantity of fluid to the tool-holder motor upon each reversal of the work-holder.

The fluid necessary to move the tool-holder is taken from the common supply, i. e., from the port 56 in the valve body 13, and is delivered to the tool-holder fluid motor cylinder after passing a manually operated tool-holder throttle valve 107 and a fluid-operated admission valve 102, which like the master valve 53 is in the nature of a free-piston.

The throttle valve 107 is manually adjusted by means of the hand lever 107' to govern the extent of the intermittent movements by regulating the amount of fluid supplied to the tool holder cylinder 34, while the valve 102 controls the timing of the tool-holder intermittent movements.

The valve 102 is a cylindrical reciprocating valve closely fitted in a horizontal bore 103 (Fig. 8) which intersects a port 101 which conveys fluid from the port 56. The port 101 is normally closed by either one of the solid portions of the valve 102, and thereby prevents movement of the tool-holder during grinding operations except at the ends of the work-holder strokes when the grinding wheel is clear of the work.

The reciprocatory movement of the valve 102 is merely a longitudinal shifting in its bore 103 under the impulse of fluid pressure admitted alternately to the ends of the bore 103, conveyed thereto, on the one hand, from the port 69', and on the other, from the port 81. Therefore the right end of the valve 102 is exposed to pressure conveyed from the right end of the pilot valve bore 66, while the left end is acted upon by fluid conveyed from the left end of the pilot valve bore 66, so that as the pilot valve is shifted at work-

holder reversals, so also is the valve 102 given a single movement from one end to the other of its stroke for each movement of the pilot valve.

It was stated that the port 101 is normally closed by the valve 102. To allow admission of fluid through this port 101 whereby the tool-holder is moved at the proper time, the valve 102 is provided at its central portion with a fluid supply opening in the nature of a narrow circumferential groove 104. During the space of time that the groove 104 is passing the ends of the port 101, a charge of fluid is permitted to pass through the port 101, and after the valve passes to the opposite end of the bore 103, this port 101 is again closed by one of the solid portions of the valve. The quantity of fluid so admitted is small because it is necessary only to overcome the friction of the tool-holder and to force a similar small quantity from the opposite side of the tool-holder motor piston. For this reason, the groove 104 is narrow, and the valve 102 admits only the fluid that is able to pass therethrough during the short space of time that elapses while the groove 104 is passing the port 101.

In Fig. 8 the position of the tool-holder reversing valve 34' is such that the intermittent movement of the tool-holder is being made rearwardly or to the left in the view, inasmuch as fluid pressure being delivered to the valve chamber from the supply conduit 39 is diverted by the valve 34' into the port 41 leading to the forward end of the cylinder 34. Fluid displaced from the opposite end flows in reverse through the port 42 again into the valve chamber, thence into an open port 40' in communication with the tool-holder exhaust conduit 40.

When the tool-holder is to be reversed so that the intermittent movements are to be made in a forward direction or to the right in the view, the reversing valve is longitudinally shifted forwardly either by contact of the stroke-limiting dog 109 with the rock-shaft lever or by manual means, whereby the fluid pressure is directed by the new position of the valve into the rear or left end of the cylinder 34 by way of the port 42, while the path for fluid displaced from the forward end of the cylinder at this time is seen to be through the port 41 and into the exhaust conduit 40 through the short port 40''. It is obvious that one or the other of the companion ports 40' or 40'' will be closed by the reversing valve 34' according to the position of the valve.

In the operation of the machine constructed according to the description just given which corresponds to that of the patent mentioned, the grinding wheel is preferably placed near an edge of the work-piece, and is fed intermittently across the work as the work-table is reciprocated. When the grinding wheel has removed all of the stock at this elevation of the wheel, the wheel is lowered manually. When the work-piece is finished and removed, the operator manually elevates the grinding wheel for a start on the next piece.

Automatic control devices

By the improvements to be now described, it is provided that at each reversal of the tool-holder, which, as before stated, is caused to occur when the grinding wheel has traversed completely across the work-piece in forward and rearward directions, the grinding wheel is automatically lowered a predetermined amount. After a desired period of this lowering or down-feeding of the tool-support this portion of the automatic cycle is stopped, not, however, with stoppage as

yet of the work-holder reciprocations or the accompanying traversing intermittent movements of the tool-holder.

One purpose of allowing the machine to continue to run without down-feeding of the tool-support is to provide a smoothing or finishing operation on the work-piece which automatically follows the down-feeding period. The smoothing operation may be known as the "spark-out" time, since evidence is given by lack of sparks from the grinding wheel that the smoothing operation is completed. The length of time the finishing or smoothing operation is allowed to continue is variable at will, and it is further provided in the improved machine that at the conclusion of the spark-out time, the work-holder is caused automatically to move to a loading position. The loading position is usually located at a far point on the base at some distance from the grinding wheel in order to further insure the safety of the operator, and after the work-holder comes to a stop, the tool-support is automatically elevated to a precise predetermined height.

25 Mechanical features of automatic down-feed and elevation for tool-support

The description that follows relates to the devices which are added to the machine constructed according to the specifications set out in the patent mentioned whereby the present improved machine is obtained.

It was previously mentioned that a housing containing certain devices pertaining to the new construction was located on the forward wall of the base 1. This housing is indicated at 140. The housing has a central opening through which the cross-shaft 22 of the tool-support elevating mechanism projects, on the outer end of which shaft the elevation hand-wheel 22' is secured.

35 On the portion of the cross-shaft 22 (Fig. 2) within the housing 140 is secured a pair of ratchet wheels 143 and 144, with which pawls cooperate. In the present instance, two pawls offset in relation to each other are used for each ratchet wheel, the pawls 145 and 146 (Figs. 5, 6 and 7) cooperating with the ratchet wheel 143, while the pawls 147 and 148 coact with the ratchet wheel 144. The pawls 145 and 146 are pivotally connected with a pawl arm 149, known as the down-feed pawl arm, rotatably carried on the hub 150 of the ratchet wheel 143, while the pawls 147 and 148 are similarly pivotally connected with a pawl arm 151, called the elevating pawl arm, rotatably supported on the hub 152 of the ratchet wheel 144. Since the pawls are located below their respective ratchet wheels, it is preferable that the pawls are spring-pressed into engagement with the ratchet wheels, compression springs such as are indicated at 153 being employed for the purpose.

60 The ratchet wheels and therefore the cross-shaft are alternately given partial rotation by hydraulic fluid motors, liquid pressure such as oil being preferred for, among other reasons, an inherent smoothness of action. The valves for these fluid motors are electrically controlled and actuated as will be brought out in the description, use being made of certain now available accurately performing switches. It will also be made clear that but one of the ratchet wheels is actuated at a time, and that each returns to a normal position wherein no interference to manual operation can be offered.

65 To transmit the motion of the fluid motors to the elevating mechanism the lower end of each

pawl arm is provided with a segment of gear teeth. Referring to the down-feed pawl arm 149 the gear tooth segmental portion is shown at 154, meshing with which is a hydraulic piston 155 in the upper portion of which rack teeth 156 are cut. In its initial stage of manufacture the piston 155 is a cylindrical rod having the rack teeth machined in its upper surface as explained. As such, the piston comprises a portion of a fluid motor, the cylinder for which is located in the lower portion of the housing 140 and is indicated at 157, as best seen in Figs. 5, 6 and 8.

The elevation pawl arm 151 is also provided with a segment of gear teeth as shown at 158, meshing with which teeth is a second rack piston 159 of another fluid motor located in the housing 140. The cylinder bore of this second fluid motor is indicated at 160 and as seen in Figs. 5 and 6 is located in a parallel position with reference to the fluid motor 157.

The hydraulic pressure by which the fluid motors perform their respective functions is derived from the main fluid pressure system through a conduit 161, Fig. 8, being branched off the main conduit 50 leading from the relief valve 51. The conduit 161 further branches forming a pair of conduits, one, at 162 carrying fluid pressure to a control valve indicated in general at 163, while the second of these branches 164 leads to a second control valve also indicated in general at 165.

In Fig. 7 it is seen that the rack pistons 155 and 159 are disposed in parallel relation with each other; as are also the rack arms and ratchet wheels; however, in Fig. 8 these parts are placed side by side in order to more clearly show their functions.

The purpose of the control valves is to control the flow of fluid pressure to and from the down-feeding and elevating fluid motors. The movable parts of the valves are actuated by electrical means and the fore part of the following description will deal first with the mechanical and hydraulic features pertaining to these valves, the description of the electrical portions being made later.

Referring to the control valve indicated at 163, the movable part thereof consists of a piston type valve 166 which has enlarged lands or spools at each end and a narrower land at the central portion.

The conduit 162 delivers fluid pressure to the central portion of the bore 167 in which the movable valve 166 is fitted, and as seen in Fig. 8, the piston valve 166 is positioned in the left end of its bore, whereby any fluid pressure entering passes to the right of the central land to a port 168 in the opposite side of the bore. This port 168 communicates by means of the conduit 169 with the right end of the bore 167 of the down-feeding fluid motor containing the rack piston valve 155, the fluid reaching this end by passing through the internal passage 169a in the housing 140 (Figs. 5 and 8). This position of the control valve 166 is maintained as a normal position, the valve being returned and retained there by a compression spring 170 located at the right end of the piston valve. By this position of the piston valve, the rack piston 155 is held at the left end of its travel, which position is the normal position of the rack piston.

The control valve 165 is identical with the valve just described. Its piston valve, indicated at 171, is maintained at the right end of its bore as a normal position by the compression spring 172, in which position fluid pressure flows to the left of

the central land through the conduit 173 and internal port 173a in the housing 140 (Figs. 7 and 8) to the left end of the second, or elevating fluid motor containing the rack piston 159 and at this normal position of the piston valve 171 the rack piston is retained in the right end of its bore as its normal position.

The purpose of causing the control valves and rack pistons to return to these normal positions as described is to permit when desired of the manual handling of the machine at which time the tool-support may be elevated or lowered manually, whereby it is possible to change over from a machine which is operated in every respect as was the machine as described in the patent mentioned to the automatic machine of the present application with no more than the mere closing of an electric switch.

In order to permit manual elevation and lowering of the tool-support, the pawls connected with the pawl arms are disengaged from contact with the ratchet wheels. The means for causing this disengagement is the use of curved pawl-withdrawing shields encompassing a part of the lower portion of the ratchet wheels. Referring to the first of these shields, there is one seen at 174 (Figs. 5, 6, 7 and 8) secured to a lug 175 on the interior wall of the housing 140. The shield is cut away as shown at 176 (Fig. 7) to accommodate the offset pawls, but each of the pair of pawls 145 and 146 is disengaged at the same time which occurs when the rack piston returns to its normal position.

The other shield is shown at 177 in Fig. 7. This shield is secured to the lug 178 similar to the lug 175 and the shield covers a portion of the ratchet wheel 144, whereby on the return movement of the pawl arm 151 due to the return of the control valve 171 to its normal position withdraws the pawls 147 and 148 out of engagement with the elevating ratchet wheel 144. Like the shield 174, the shield 177 is cut away at 179 whereby each pawl 147 and 148 leaves the ratchet wheel 144 at the same time.

45 Electrical features of down-feed of tool-support

The parts just described constitute the mechanical and hydraulic lowering and elevating means, the actuation of which is dependent on electric switching arrangements such as will now be described.

It will be observed that the difference between the ratchet wheels 143 and 144 is merely that the ratchet teeth point in opposite directions, thus, with an angular partial rotation of the pawl arm 143 from its normal position as seen in Fig. 5, the pawls 145 and 146 will slip off the shield 174 into engagement with the ratchet teeth and turn that wheel 143 in an anti-clock-wise direction. It will be understood that since the elevating ratchet wheel 144 is also keyed to the cross-shaft 141 that this ratchet wheel also at this time turns in an anti-clock-wise direction, but with no effect since the pawls 147 and 148 are kept from contact with the ratchet wheel 144 by riding on their shield.

In the present machine, clock-wise rotation of the hand wheel 142, whether by manual or automatic means, results in an elevation of the tool-support, while anti-clock-wise rotation of these parts produces a lowering of the tool-support.

70 Therefore, to produce a lowering of the tool-support and grinding wheel by the automatic electro-hydraulic means, the rack piston 155 is moved to the right, imparting a partial rotation to the rack arm 148 in an anti-clock-wise direction.

The automatic elevation, the control for which

will be fully described later, is effected by a movement of the rack piston 155, which causes the pawls 147 and 148 to slip off the disengaging shield 177 to engage the teeth of the ratchet wheel 144 to impart to this ratchet wheel a partial rotation in a clock-wise direction.

As before stated, the control valve 163 controls the movement of the rack piston 155. The means for actuating the control valve itself consists of electrical equipment including a solenoid to move the valve, a time relay to provide a variable time lapse and a switch to energize the time relay and with it, the solenoid.

The automatic down-feeding movement of the tool-support is timed to occur when a complete traverse of the grinding wheel across the work-piece has been made, and before the grinding wheel starts on the following traversing movement. The shifting of the tool-holder reversing valve 34' when the reverse of the tool-holder is made provides a means for bringing about the energization of the electrical portions of the down-feed arrangements.

In that part of Fig. 8 in which electrical circuits are shown, the circuits consist of suitable pilot current and power current circuits. The pilot circuits are shown in light lines, while the heavier lines indicate power circuits. The power circuits are preferably employed in carrying current to and from the electro-magnets to be described.

On the valve stem extension 28 of the tool-holder reversing valve 34' there is secured a cam 178 which closes a switch 180 during the reversing reciprocations of the tool-holder valve. The switch 180 is a single-pole, single-throw switch and as seen is only momentarily closed, the movable member of which is a spring arm so that the switch opens immediately after the passage of the cam 178 thereby, and with the rod as shown, the switch 180 is actuated for each movement of the valve 34' whether the valve is moved forwardly or rearwardly.

The closing of the switch 180 results in a flow of pilot current indirectly to a down-feed electromagnet in the form in the present case of a solenoid 181 (lower left portion, Fig. 8) the movable armature of which is connected to an outer extension of the down-feed control valve 166, whereby the energization of this solenoid results in a shift of the valve 166 to the right. This movement then results in a flow of fluid pressure to the left end of the down-feed rack piston 155 to bring about a down-feed of the tool-support 31, as described.

The movement of the valve 166 by reason of the energization of the solenoid 181 is made against the compression of the valve return spring 170, therefore, when the solenoid 181 is deenergized, the spring 170 returns the valve and the connected solenoid armature to the normal position at the left end of the cylinder of the valve body 163. This return of the valve reverses the fluid flow to the down-feed rack piston 155 and causes it to move to its normal position at the left end of its travel. As before mentioned, at this position the pawls 147 and 148 are disengaged from the ratchet wheel 144, so that if the operator should desire, he may manually operate the elevation mechanism without interference by the pawls.

In explanation of the statement that the down-feed switch 180 is closed only momentarily, it should be made clear that the reason for this feature is that in order to be effective for the next following down-feed in automatic cycle grinding operations, the switch should be normally open.

5

The following down-feed is due to occur at the next following tool-holder reversal, during which event the cam will approach, actuate and pass by the switch. It will likely, also, be evident, however, that momentary closing of the switch 180 will provide an energization of the solenoid 181 of such short time duration that the hydraulic members of the down-feed arrangement will have insufficient time in which to carry out the functions for which they are intended. Consequently an electrical timer relay device is interposed between the down-feed switch 180 and the solenoid 181 such that will prolong the energization of the solenoid 181 for a suitably long period of time.

Before the description of the timer relay is made, an explanation of another switch which acts in conjunction with the down-feed switch 180 will be brought in. The switch in question acts to terminate the down-feeding portion of the automatic grinding cycle, and further starts the machine on that portion of the cycle previously mentioned as the smoothing or spark-out operation.

On the vertical slide 31 which carries the tool-holder there is secured an adjustable dog having a means for obtaining the precise adjustment in keeping with the accuracy of which the machine is capable. The dog (Figs. 4 and 8) consists of a body 182 which is secured to a T-slot bar 184 which in turn is secured to the vertical slide 31, by the use of which T-slot bar the dog is readily adjustable so as to suit different working conditions. For the more precise adjustments mentioned, there is secured to the T-slot bar 184 above the dog 182 an anchor block 185. The switch contacting dog 182 and the anchor block 185 are connected together by a screw 186 preferably of a micrometer type, the screw being provided with a comparatively fine thread and graduated indicia on an enlargement of the screw. By loosening the T-bolts 187 and 188, both dog and anchor block may be shifted to any position on the T-slot bar 184 as a unit, while the precise adjustment may be made by tightening the anchor block and moving the contacting dog 182 by means of the micrometer screw.

The contacting dog 182 operates the movable element 189, Fig. 8, of a single-pole, double-throw switch 188 mounted on the column 33, Figs. 1, 2 and 4. The movable member 189 is spring-pressed so as to be maintained normally closed against the stationary contact 191; that is, the right side of this single-pole double throw switch is normally closed. As the vertical support 31 descends during the down-feeding portion of the automatic cycle, the contacting dog eventually makes contact with a cam lever 192 pivotally mounted on a bracket 193 secured to the column 33 in such position that a plunger 194 transmits the motion received from the dog 182 to the movable switch member 189. Should the vertical support or slide 31 be lowered, as during manual operation of the machine, below the cam lever 192, the contacting portion of the dog 182 will lift and rotate partially the cam lever when the slide is again elevated, the lever returning by gravity to its normal position as seen in the diagram.

While the vertical support or slide 31 is held at an elevation such that the contacting dog 182 is above the bell-crank 192 as seen in Fig. 1, the right side of the double-throw switch is closed. Pilot current therefore flows through this side of the switch from the pilot current supply switch 195. From this supply switch a conductor 196 carries pilot current which divides into two cir-

60

65

70

75

cuits. One circuit 197 leads to several switches (to be referred to later) while the other circuit as represented by the conductor 198 leads to the movable element 189 of the double-throw switch 190 previously mentioned, and through the right side of this switch (the normally closed side) through the conductor 199 to the down-feed switch 180.

Thus, the down-feed switch 180 and the right side of the switch 190 are in series, which allows that the tool-support will be intermittently lowered and the grinding wheel 24 will remove stock from the work-piece, so long as the dog 182 is apart from the cam lever 192, for at each reversal of the tool-holder pilot current will flow to the down-feed switch 180 from the still closed right side of the switch 190 then through the conductor 200 to the timer relay indicated in general at 201 (Fig. 8 only).

The timer relay is so-called since on application of current to it by the closing of a momentarily operated switch as is the case here, its relay switch 209 may be maintained in an opened or closed condition as desired for a variable length of time, though the electrical impulse that caused the actuation of the relay switch has been cut off by the opening of the switch 180. The means for providing the delay is on the order of a dash-pot in which there is fitted a piston, the piston rod of which actuates the relay switch.

The dash-pot cylinder is indicated at 202, the piston at 203 and the preferably non-ferrous piston rod at 204. The piston is normally retained in the lower portion of the cylinder by a compression spring 205, a boss 206 on the lower side of the piston acting as a stop to limit the downward movement of the piston. To raise the piston 203 by the closing of the down-feed switch 180, the pilot current flows from the conductor 200 through an electro-magnet in the form in the present case of a solenoid coil 207 surrounding the piston rod, a portion 208 of which rod is of magnetic material such as iron serving as an armature whereby the magnetism set up by this energization of the coil will attract the armature to lift the piston 203. Although this coil 207 is known as a holding coil when speaking of relays in general, it should be understood that its energization is momentary only, and that the coil does not hold the movable parts of the relay. The return of pilot current to the supply switch 195 is through the conductor 207.

The upward movement of the piston and other movable parts occurs suddenly on the single momentary impulse delivered to the coil 207 by the closure of the down-feed switch 180, which as explained before immediately opens and the coil is also immediately de-energized. But the energization is sufficient to cause elevation of the movable members of the relay which then start to descend. As soon as the upstroke is started a relay switch 209 previously mentioned as receiving pilot current from the conductor 197 is allowed to close. This relay switch 209 is a single-pole, single-throw switch, and although it would ordinarily be classed as a normally closed switch in view of the action of the spring 210 on the movable member 211 of the switch, it is held open except when a down-feed is to be made by reason of an arm extending laterally from the piston rod 204. This arm 212 is secured to the upper end of the piston rod and extends over the movable switch member to thereby make contact with this member to open

the switch by reason of the greater strength of the dash-pot spring 205.

The upward movement of the piston carries the arm 212 to an elevation as shown in broken lines which is somewhat above the point where the movable member 211 of the switch will stop when it makes contact with the stationary part 213 of the switch, a limit for the upward movement being provided in the form of a boss on the upper side of the dash-pot piston 203.

It was stated that the upward movement of the piston and connected movable parts of the relay was made suddenly. It will be explained that a rapidly made upward movement is not essential to the proper operation of this timer relay, but is only incidental. The time lapse is measured from the time the relay switch 209 is allowed to close by relieving the pressure of the arm 212 on the switch to the time when the switch 20 is again opened by the descending arm and to provide the time lapse, the descent is made at a relatively slow rate as desired. As is usual with dash-pot arrangements, one stroke may be made at a rapid rate, while the other may be made at 25 a slower rate. In the present case, displacement of some medium such as air at an adjustable relatively slower rate provides for the slower descent.

On the up-stroke, the air displaced from the 30 upper portion of the dash-pot cylinder 202 flows to the lower part of the cylinder, where at this time suction is occurring. Two passages are provided for the transfer of this displaced air, one passage being shown on the right side of the dash-pot cylinder through an externally positioned non-return check valve 214, and another passage shown at the left side of the cylinder as indicated at 215. The check valve offers little resistance to the downward flow of the displaced 40 air, but prevents return therethrough, whereby such air must return to the upper portion of the cylinder on the down-stroke of the piston through the passage 215. To impart a desired variable 45 descent rate, a needle valve 216 is interposed in the passage 215, whereby the flow of displaced air is subject to the restriction offered by the manner in which the needle valve is adjusted.

The closing of the relay switch 209 on the upward stroke of the relay parts allows pilot current to flow through a conductor 211 to an electro-magnet in the form of a power contactor 218 (lower central part of Fig. 8) adapted to handle the heavier power current taken from the power main 219 leading from the power current switch 220 (upper right portion, Fig. 8). The return of pilot current from the contactor 218 is shown at 221, this conductor leading to the pilot current supply switch 195.

The energization of the power contactor 218 60 permits power current to flow through a conductor 222 to the previously mentioned solenoid 181 (left lower portion, Fig. 8) a conductor 224 forming the other part of this circuit and being in connection with the power main switch 220.

Energization of the solenoid 181, which may be 65 termed the down-feed solenoid, brings about a lowering or down-feed of the tool-support as mentioned before, inasmuch as the down-feed control valve 168 is shifted and fluid pressure then flows to the left end of the down-feed rack-piston 155 through the conduit 169' and internal port 169b causing an anti-clockwise partial rotation of the ratchet wheel 143.

It can be seen that momentary energization 70 only of the down-feed solenoid 181, as would be

the case had the simple switch 180 been employed without the added timer relay, the operation of the valve moving solenoid 181 would have been interfered with, likely to the extent that the pawls would not move so far as to engage the teeth of their ratchet wheel. With the timer relay, however, a sufficient time lapse is given to insure that the down-feed mechanism may make its full intended stroke of whatever length desired within the capacity of the mechanism, and during this time, the machine is continuing in its automatic grinding cycle.

While the timer relay 201 is maintaining energization of the down-feed solenoid 181, the control valve 166 is being retained at the right end of its stroke against the compression of the valve spring 170. It is evident that the valve must be returned to its normal position before another down-feed stroke can be made, consequently the solenoid must be de-energized. This is brought about when the timer relay arm 212 descends sufficiently to open the relay switch 209, and the needle valve 216 may be so set as to allow the opening of this relay switch 211 as soon as it is certain that the down-feed rack piston 155 has made its full intended stroke. In practice, the time lapse is of less than a minute in duration, being measured rather in seconds than otherwise.

Following the opening of the relay switch 211, de-energization of the down-feed solenoid occurs, the valve spring 170 forces the control valve 166 to the left to thereby return the rack piston 155 to the left, withdrawing the pawls from engagement with the down-feed ratchet wheel 143.

The distance the tool-support may be automatically lowered is variable, the adjustment for which is provided by a screw 225, Figs. 5 and 6. As seen in these figures in connection with Fig. 7, the screw 225 is positioned in the path of the rack arm 149 whereby the angular stroke of this member may be varied from a full stroke as offered by the full travel of the rack piston 155 to the right, in which event the screw is backed out sufficiently to permit this full stroke, to a partial stroke, such as is shown in Fig. 6, wherein the screw 225 is shown turned in to stop the rack arm 149 before the full stroke is made. It will be understood that the down-feed stroke, whatever the adjusted length may be, is always made from the normal position of the rack arm and piston 155 at the left of its travel as seen in Fig. 5 wherein the pawls are shown disengaged from the ratchet wheel.

When the tool support 31 has been automatically lowered the predetermined distance (upper right portion, Fig. 8) the dog 182 on the support makes contact with and actuates the cam lever 182 to break the circuit that controls the down-feed devices for the support by moving the movable contact member 188 of the switch 190 out of contact with the member 191.

Smoothing out of work

The cam lever by its movement also shifts the movable member 188 of the switch 190 in contact with the stationary member 228 of the switch 190 and thereby closes another circuit whereby another sequence in the automatic grinding cycle is started, this being the smoothing or "spark-out" operation previously referred to. This is followed by the automatic return of the work-holder to the loading position, and the elevation of the vertical slide to the proper height for a start for automatic grinding on the next work-piece.

The closing of the left side of switch 190 starts a second timer relay 228 which controls the movements of the work-holder to loading position and the elevation of the tool support and also by reason of a slow closing thereof allows for a smoothing out period. This relay 228 is of slightly different construction from the timer relay 201 since it is not employed for the purpose of permitting a time lapse during which a fluid motor may make a stroke, but to provide a variable time period for the smoothing or spark-out time before the reciprocation of the work-holder is ended and the work-holder moved to loading position.

When the left side of the switch 190 is closed, pilot current flows through a conductor 226' to the electromagnet in the form in the present case of a solenoid coil 228 of the second timer relay (center right portion, Fig. 8 only) indicated in general at 228 to be known as the smoothing or spark-out timer relay. The energization of this coil results in the elevation of a rod 230 having an armature portion 230' which further results in the relatively sudden lowering of the forked left side 231 of a pivoted double-armed rocking lever 232, to which the rod is pivotally connected. This movement of the lever 232 is accomplished against the tension of the spring 233, so that when the coil 228 is deenergized, the lever and armature are returned to their normal position as seen in Fig. 8.

Through the use of the spring 233 in so retaining the lever 232, the piston rod 234 and piston 235 of this timer relay 228 are held in their normal upper position in the relay against the compression of the spring 236, this spring being preferably relatively weak as compared to the lever spring 233. At the upper end of the piston rod is a laterally projecting arm 237 in position to make contact with the relay switch indicated in general at 238. This switch has a movable, spring-operated contact element 239 having a projecting extended end positioned so as to be depressed by the arm 237 when the same is lowered by the spring 236 on energization of the solenoid coil 228.

The descent of the movable portions of this timer relay, by which is meant the piston and piston rod, is made at a suitably slow rate such that will provide the desired time for the smoothing or spark-out operation. The duration of time allowed for the spark-out operation is that time taken up during the downward approach of the arm 237 toward the relay switch 238, and when the arm makes contact with the movable switch member 239 and forces this member in contact with the stationary element of the relay switch 238 to close this switch, this closing marks the end of the spark-out time, following which the work-holder will be removed to the loading position.

Portions of the timer relay just described are much like those described in connection with the explanation of the first mentioned down-feed timer relay 201, the similarity being in the manner in which the displaced air is metered in its flow from opposite ends of the dash-pot cylinder. The regulation of the rate of descent is effected by the adjustment of a needle valve 240 which is employed to suitably restrict the flow of air from the lower to the upper end of the cylinder 241. A non-return check valve 242 is employed to allow free flow of displaced air from the upper to the lower end of the cylinder and to prevent a reverse flow therethrough, forcing the displaced

air to pass by the needle valve 240. The same comment as to it not being essential that the timer relay should move at a rapid rate on its idle stroke made in connection with the description of the down-feed timer relay 201 applies to this second timer relay 229.

Before going into the explanation of what follows when the relay switch 238 of the spark-out timer relay 229 is closed, it will be explained that the spark-out timer coil 228 remains energized during the spark-out time in order to delay the opening of the contacts of this relay, since, to properly carry out the smoothing or spark-out operation, it is necessary that the grinding wheel remain at the desired low point it reached when the left side of the double-throw switch 180 was closed. It will be further evident that during the spark-out operation, no down-feeding is to be made, and such is not made, although the down-feed switch 180 is being repeatedly closed at each reversal of the tool-holder traversing movements; but, since the right side of the double-throw switch 180 which is in series with the down-feed switch 180 was opened when the grinding wheel reached the adjusted depth, no further down-feeding is possible because the circuit which controls the power relay 218 is now broken.

Return of work-holder to loading position

At the conclusion of the spark-out operation which occurs when the spark-out relay switch 238 is closed, reciprocation of the work-holder is arrested and the work-holder is automatically returned to the loading position, a portion of which return stroke is made at a reduced rate of movement and also the tool support 31 is elevated to the upper starting point.

In reference to the description of the manner in which the work-holder is returned to the loading position it will be pointed out that in the routine grinding operation, whether after the manner as described in connection with a machine constructed according to the patent mentioned or according to the design of the present application, that the range of reciprocations of the work-holder is normally confined to a portion of the machine by the spacing of the work-holder reversing dogs 14 and 15. To move the work-holder automatically to a portion of the base that may be outside the normal grinding stroke as set by these dogs means that one of the reversing dogs must be rendered temporarily ineffective to cause a work-holder reversal. Of several methods that may be available, the following is preferred as it lends itself to automatic operation of the machine and does not involve a readjustment of one of the reversing dogs for this purpose.

In the present case, the loading position is at the right hand end of the base of the machine, and this means that the left hand dog 14 is the one which is to be made ineffective to allow the work-holder to move to the loading position. It is this dog 14 which indirectly will cause a shifting of the master valve 53 when the work-holder is moving toward the right and the dog strikes and rocks the reverse lever 18, but, to allow the work-holder to move on by the point where it would ordinarily be reversed, the master valve is not shifted although the pilot valve 23 is shifted as usual.

By the devices to be described the master valve 53 is not shifted by the left hand dog 14 at this time because the fluid pressure under control

of the pilot valve 23 which ordinarily would bring about a shift is now temporarily blocked from reaching the master valve. The blocking means was previously referred to in connection with explaining the manner in which the master valve 53 is shifted under the normal control of the pilot valve 23, where it was stated that fluid pressure flowing through the passage 88 eventually to arrive at the right hand end of the master valve bore is conveyed externally through the external conduit 243 in communication with the port 88 to the blocking device indicated at 89 (right central portion, Fig. 8) and from this device through the conduit 245 to the right end of the master valve bore.

The blocking device 89 is in the present case a solenoid operated hydraulic valve, the solenoid being indicated at 246. The movable part is in the form of a grooved piston valve connected to the solenoid, the valve being spring-returned in order that it and the armature of the solenoid may be restored to the normal position when the solenoid is deenergized. The valve is shown at 247, the groove mentioned being indicated at 248, while the spring is seen at 249. The effect of the spring is to maintain the valve normally so that the circumferential groove 248 is in registry with the port openings in communication with the external conduits 243 and 245 whereby a free flow of fluid pressure is permitted to pass to the right end of the master valve except at the time when the work-holder is to be moved to the loading position.

As stated, this movement is under the control of the spark-out timer relay switch 238 which in turn is controlled by switch 180. When this switch 238 is closed as described at the end of the grinding and smoothing or spark-out operations, pilot current taken from a continuation of the conductor 197 flows through a conductor 238' which leads to and energizes a power contactor relay 250 (lower right portion, Fig. 8), which in turn allows power current taken from the power main conductor 218 through a conductor 251 to energize the blocking valve solenoid 246, the return flow conductor for the pilot current being shown at 250', and for the power current at 252. The effect of energizing the blocking solenoid 246 is to depress the valve 247 to place the circumferential groove out of registry whereby the fluid pressure flow from the pilot valve is blocked. This obviously prevents a movement of the master valve such as ordinarily occurs when the pilot valve 23 is shifted and therefore the work-holder continues on its stroke to the right and moves to the loading position at the right.

It should be explained that the dogs 14 and 15 are offset with relation to one another as are likewise the lugs 16 and 17 so that the lug 16 will stand in the path of the dog 14 and the lug 17 will stand in the path of the dog 15. When the work-holder is moved to loading position the dog 14 striking the lug 16 will throw the lever to the right and the dog will then ride over the lug as the work-holder moves to its loading position. Upon the return movement of the work table the dog 14 will ride over the lug 16 and pass at one side of the lug 17 and the dog 15 will ride at one side of the lug 16 and strike the lug 17 to again shift the pilot valve.

In the explanation of the method by which the master valve movement was blocked by the energization of the blocking solenoid 246, it must also be brought out how this solenoid is deener-

gized, mention of this part of the explanation being made at this point in order to make it clear that, while this blocking solenoid is energized by the closing of the switch 238, the opening of this same switch does not bring about de-energization of the solenoid 246, this being the function of another switch 264 which is manually actuated by the operator in re-starting the automatic cycle.

It will be remembered that with the master valve 52 in its right hand position as seen in Fig. 8, as long as the blocking solenoid is energized, the work-holder will continue to move toward the right until it stops at the loading position, which may be when the work-holder reaches the end of the base or the end of the cylinder of the work-holder fluid motor 5 where it will be retained by reason of fluid pressure on the left side of the piston. It is also clear that should the blocking solenoid 246 be deenergized, the work-holder would immediately reverse itself and move to the left, the pilot valve 23 having already been shifted. It is one of the purposes of this construction to provide that the work-holder be moved to the loading position and to be retained in that position for as long as the operator may desire. It is a further purpose that the tool-support 31 be automatically elevated when the work-holder reached the loading position, which elevation will open the left side of the double-throw switch 190. This in turn will cause deenergization of the spark-out timer relay solenoid coil 228 whereby the spring 233 will cause the opening of the relay switch 238, with deenergization of the blocking solenoid 246 and, if not prevented, consequent immediate re-start of the work-holder. Obviously, this is not desirable inasmuch as the operator should have ample time in which to re-load the machine. Before the explanation is made of the manner in which the solenoid 246 is controlled jointly by two separate switches, a description will be made of the means whereby the speed of the work-holder is reduced as it approaches the loading position.

Speed retarding device for work-holder when moved to loading position

The retarding device is a valve arrangement interposed in the work-holder fluid motor exhaust conduit. The device is indicated at 253 (right center, Fig. 8) and contains a grooved, spring-pressed piston valve 254 similar to the blocking valve 241. In the normal position of the retarding piston valve 254 as effected by the valve spring 256, a free flow of exhaust fluid is afforded by the registry of the circumferential groove 257 with ports in the cylinder wall which are in communication with the exhaust conduits 64 and 64'. It can be seen that depression of the retarding valve will reduce proportionately the speed of the work-holder. To bring about this speed reduction, a retarding cam 258 (left center, Fig. 8) is attached to the T-slot of the work-holder, in the present case, between the pair of work-holder reverse dogs 14 and 15.

The lower portion of the cam is formed with an offset to pass the reverse lever 18. When the work-holder moves sufficiently far toward the right, the lower upwardly sloping cam surface 259 makes contact with the retarding valve 254, this valve having an upward extension projecting through the upper portion of the valve cylinder 255. To provide that the depth to which the retarding valve is depressed may be adjustably regulated, the valve stem extension is fitted with

75 a threaded tappet screw 260. As seen in the right central portion of Fig. 8, the retarding cam is shown in dot-dash lines in position to make contact with the tappet screw 260 to depress the valve stem and its valve 254 whereby the groove may be somewhat out of registry with the ports. A reduced flow will thereby be permitted, it not being the intention to cut off entirely the flow of exhaust fluid.

10 The work-holder will continue to move at the reduced rate of speed toward the right, the retarding valve now being held at the desired depth of the horizontal under portion 259' of the cam 258 until the work-holder abuts against a stop, 15 which may be of any nature, such as when the piston 6 of the work-holder fluid motor 5 reaches the right cylinder head of this fluid motor. This is a dead stop, and as was mentioned previously, the work-holder will be retained at this point by fluid pressure. It may be noted that with this method it is not necessary to alter the work-holder speed control throttle 58, whereby the operator is further relieved of some responsibility in this connection.

20 At about the same time that the work-holder reaches the actual stop or loading position, a switch 262 (right central portion, Fig. 8) which may be known as the slide elevation switch, is closed by the upper portion 263 of the retarding cam 258. The slide elevating switch is a normally open switch and is in series with a normally closed manually operated switch 264 to be referred to later, known as the re-start switch. Pilot current is taken from a continuation of 25 the conductor 197 on closing of the tool-support elevation switch 262 and passed through the re-start switch 264 which is a normally closed switch, and through a conductor 266 to the coil 268 of an interlocking relay 267 (right central 30 portion, Fig. 8). From this coil 268, the pilot current is returned to the conductor 221 leading to the pilot current supply switch 195.

35 One purpose of this interlocking relay 267 is to provide that the energization of the blocking solenoid 246 which was initiated by the closing of the left side of the double-throw switch 190 and which caused the movement of the work-holder to the loading position, is maintained by the interlocking relay, because as was explained, as soon as elevation of the tool-support 31 is permitted, the accompanying opening of the left side of the double-throw switch 190 would, without the use of the interlocking relay, have caused the deenergization of both the spark-out timer relay 40 and the blocking valve solenoids 228 and 246, with the consequent immediate re-start of the work-holder. To put the re-starting under the manual control of the operator is the function of the interlocking relay.

45 When the coil 268 of the interlocking relay 267 is energized by the closing of the switch 262, two circuits are established. One is a pilot current circuit that takes over the energization of the blocking valve solenoid 246. Pilot current from the conductor 197 is delivered to one of the 50 contacts of the interlocking relay 267, and from a companion contact point of this relay through a short (in this showing) conductor 288 to a junction with the previously mentioned conductor 238' leading to the power relay 266. Therefore, regardless of the position of the left side of the double-throw switch 190 or the spark-out relay switch 238, the blocking valve will be retained in position to maintain the work-holder 55 in the loading position.

Tool elevating device

The other circuit closed by the elevation of the interlocking relay 267 is a power circuit whereby the tool support 31 is elevated. Power current is taken from the power main 219 through a conductor 270 to the interlocking relay 267 and from this relay through a power conductor 271 to an electro-magnet in the form, in the present case, of a solenoid 212, to be known as the tool-support elevation electro-magnet, which is connected with the previously referred to pilot control valve 171. When the elevation solenoid 212 is energized the valve 171 is moved to the left, whereby a flow of fluid pressure through the conduit 173 to the port 173b at the right end of the slide elevating rack piston 159 is permitted, so that as this rack piston moves to the left the pawls 147 and 148 ride off of the pawl shield 177 (Fig. 5) and engage the ratchet wheel 144 to thereby elevate the tool-support 31 through the medium of the shaft 22, pinion 21, gear 21 and screw 20. The rack piston 159 remains at the left position until a manual operation of the switch 264 is made which will be explained later.

The elevation of the tool-support 31 is accomplished in a single movement in contrast with the successive, comparatively small down-feeding movements, and the amount of elevation is the sum of the down-feeding movements, therefore, the tool-support is returned to the same height as before. Inasmuch as the total amount of down-feeding is variable by the manner in which the down-feeding limiting dog 182 is adjusted with respect to the double-throw switch 180, the amount of elevation should be made equal to the total down-feed movement. This is provided for by the use of a stroke limiting screw 273 similar to the adjusting screw 225 by which, as explained before, the stroke of the down-feed pawl arm 149 is determined. The elevation limiting screw 273 is best seen in Fig. 5 at the left side of this view. It should be made clear that the angular stroke allowed the down-feed pawl arm 149 by the manner in which the stroke limiting screw 225 is adjusted does not affect the total down-feed amount; the position of the screw 225 merely provides that the total amount of down-feed is broken up into a number of comparatively small, successive down-feed movements.

Deenergization of spark-out timer relay

The automatic elevation of the tool-support obviously opens the left side of the double-throw switch 180 whereby the coil 228 of the spark-out timer relay is deenergized. The return spring 233 of this relay acts to restore the movable parts of the relay to the normal position, opening the relay switch 238. Displacement of air during the upward movement of the parts is made freely through the check-valve 242, and it will be clear as mentioned in the similar case of the down-feed relay, that it is not essential that a rapid up-stroke of these relay parts is made.

Return of blocking valve of work-holder motor to normal position

Opening of the relay switch 238 does not, however, cause deenergization of the blocking device solenoid 246, but it will be evident that if either of the switches 262 or 264 is opened, that the interlocking relay 266 will be deenergized since these switches are in series with each other and with the coil 228 of the interlocking relay 267.

The purpose of the re-start switch 264 is then clear, for when the operator desires to again start the machine, it is necessary only to open this switch 264. By this opening the coil 266 of the interlocking relay is deenergized and the two described circuits that were closed when the relay was energized are now broken. The deenergization of the blocking valve solenoid 246 is one result, as the relay 266 which supplies power current thereto will be deenergized, following which the blocking valve is forced upwardly by the action of its return spring 248, whereby the flow of fluid pressure from the already shifted pilot valve 23 that had been restrained is now allowed, by the registry of the groove 248 with the ports, to continue in its flow to the right end of the master valve 53. The resulting shift of the master valve 53 admits fluid pressure to the right end of the work-holder fluid motor 5 to start the work-holder to the left. The movement will be comparatively slow at first until the retarding cam 258 is moved off the retarding valve 255 whereupon the speed of movement of the work-holder is accelerated to its former grinding rate.

Deenergization of tool-holder elevation solenoid

The other circuit that is interrupted by the manual opening of the re-start switch 264 results in the deenergization of the elevating solenoid 212, as a consequence of which the elevation control valve 171 connected therewith is returned to its normal position toward the right by the action of its spring 172. The elevating rack-piston then also moves to the right to its normal position, since the control valve 171 is returned to the right by the spring 172, and fluid pressure is admitted to the left end of the elevating rack-piston to swing pawl arm 151 anti-clock-wise, thereby withdrawing the pawls 147 and 148 from engagement with the elevating ratchet wheel 144. As might be inferred, the return to normal position of the automatic hydraulic elevating devices may be allowed to take place while the automatic grinding cycle is again in progress. Fluid that is exhausted from the elevating control valve 166 and from the down-feed valve 168 as well is returned to the main exhaust fluid conduit 64 by means of the manifold 171.

Although a dresser or wheel truing device is not shown in the present application, it is evident that it will be found necessary from time to time to true the grinding wheel. Compensation for the reduction in grinding wheel diameter by truing is had by manually lowering the tool-support 31 a suitable amount. If the manual lowering is in the same amount as half the reduction of wheel diameter by truing, the lowermost portion of the grinding wheel periphery, the grinding contact surface, is again at the same elevation with respect to the surface of the work-holder. However, without a certain slight readjustment of the descent limiting dog 182, the next work-piece to be finished in the automatic cycle would be left too thick by the amount dressed off one side of the wheel. To compensate for this possible error, the dog 182 is adjusted upwardly a distance equal to the distance the tool-support was lowered manually. It so happens that at times the amount removed by truing or natural wear is comparatively slight, perhaps merely .001" or .002", whereby the purpose of the micrometer screw 186 is clear, since a precise adjustment of the dog is possible. It will be

understood that the anchor block 185 is not loosened for this adjustment.

It will be explained that the machine as constructed and operated in practice is capable of such accuracy in repetition that with work-pieces of comparatively uniform thickness, that it is not necessary to make any alteration to the tool-support position as regards elevation, from the position in which it was left at the last movement of the work-holder when the latter was moving to the loading position. That is, the position of the grinding wheel as regards its relation with the forward or rear edge or center of the work-piece may have been at random when the work-holder moved to the loading position. If the re-loading of a new work-piece is not made inconvenient by this random position of the grinding wheel, there is no need to alter its position and the next grinding cycle may start at once on the new work-piece. However, if the operator desires, he may so adjust the control devices, particularly referring here to the needle valve 240 of the spark-out timer relay so as to prolong or make shorter, as he desires, the time allowed for the smoothing or spark-out operation whereby the closing of the relay switch 238 is timed to occur when, say, the grinding wheel is nearly or is fully retracted.

It should now be clear that the grinding machine of this application is similar in general design to the machine of the patent mentioned and that the devices by which the automatic grinding operations are carried out as described are to be considered as additional elements made auxiliary to the design of the machine of that patent. By the added elements, a grinding machine is made possible, the operation of which is sufficiently automatic in character as to permit that comparatively large volume of acceptable work is turned out by operators of relatively limited experience.

Further, if it is desired to operate the improved machine of the present application according to the principles as set out in the patent, it is necessary only to open the pilot current supply and power current supply switches. In so doing, all the electrical circuits shown in the diagrammatic Fig. 8 are for the time being taken out of service and the several compression or tension springs function to retain the control valves or like members in their respective normal positions. This statement more particularly relates to the springs 170 and 172 controlling the down-feed and elevating valves 166 and 171 whereby the pawls are retained disengaged from the ratchet wheels.

Operation of devices

Down-feed of tool-support.—With the work-holder and tool-holder reciprocating and tool-support at its uppermost position, the tool-support is fed by step-by-step toward the work as follows: The contacts 189 and 191 of the switch 190 being normally closed, pilot current is fed to the switch 180 so that at each reciprocation of the valve stem 26 of the tool-holder reversing valve 34' pilot current will be fed through the conductor 200 to the solenoid coil 207 of the time relay 201, permitting the switch member 211 to close and thus feed pilot current from conductor 197 through conductor 217 to the power relay 218, which closes a power circuit to the solenoid 181 to operate the valve 166 of the motor rack piston 155, which, through the pawl arm 149, pawls 145 and 146, ratchet wheel 143, shaft 22, gears 21 and 75

21' and screw 20 lowers the tool-support 31 one step to the extent allowed by the adjusting screw 273. The relay 201 delays deenergization of the solenoid 181 to allow the mechanical devices time to operate. The step-by-step feed continues until the dog 182 on the tool-support contacts the cam lever 192 which through the stem 184 throws the movable contact member 189 of the switch 190 to the left which breaks the pilot circuit 199 to the switch 190 so that no further current will be supplied to the time relay 201 and therefore no further current supplied to the power relay 218, whereby the solenoid 181 will cease to function and the down-feed of the tool-support will be arrested.

Smoothing out of work period.—The next operation is to smooth out the work before the work-holder has ceased to reciprocate and is moved to loading position. Time is allowed, therefore, for 20 the smoothing out operation by delaying the automatic return to loading position of the work-holder and also for the elevation of the tool-support as follows: When the dog 182 breaks the contacts 189 and 191, it moves the contact 189 to 25 close with contact 226 so that pilot current will flow through the circuit 226' to the solenoid coil 228 of the time relay 229, this being a relay in the pilot circuit which delays flow of pilot current to the power relay 250 through circuit 197 and 30 238' which when closed permits power current to flow to the solenoid 246 which operates the valve 247 to block supply of fluid to one end of the cylinder of the fluid motor that reciprocates the work-holder. The contacts of this relay 229 are slowly closed and before closing the smoothing out operation is permitted.

Return of work-holder to loading position.—When the contacts 189 and 226 of the switch 190 are closed, solenoid coil 228 of relay 229 is energized through circuit 226' and the contacts of relay 229 are closed by delayed action thereof sufficient to allow the smoothing out operation. Pilot current then flows to the power relay 250 through the conductor 238' to close the power circuit to the solenoid 246 to move the valve 247 to block fluid supply to one end of the work-holder reciprocating fluid motor to allow the motor to move the work-holder to loading position. When the work-holder moves to loading position it closes the switch 262 and allows pilot current to flow through the conductor 265 to the coil 266 of an interlocking relay 267. When the contacts of the relay 267 are closed pilot current will then be supplied to the power relay 250 through the circuit 197, contacts of relay 267, and circuits 269 and 238' to maintain the blocking valve in blocking position to allow time for placing a new work-piece on the work-holder, this condition prevailing until the manually operated switch 264 is opened by the operator; one purpose of the interlocking relay 267 being to maintain the power relay 250 energized when the contacts of the time relay 229 are opened by the breaking of the circuit 226', which follows so soon as the interlocking relay 267 is energized, for the closing of the relay 267 also closes a power circuit which elevates the tool-support 31, permitting the breaking of the contacts 189 and 226 of the switch 190 and hence the breaking of the pilot circuit 226'.

Elevation of tool-holder.—When the interlocking relay 267 is closed in the manner described a power circuit is established through the solenoid 272 to operate the valve 171 to permit fluid to flow to the right end of the cylinder 160 to move the rack pinion 159 to the left so as to

swing the pawl arm 151 clock-wise and engage the pawls 147 and 148 with the ratchet wheel 144 and thus elevate the slide through the medium of the shaft 22 and the gears 21 and 21' and screw 20, which elevated the tool-support 31.

Modification of tool support feeding mechanism

In Figs. 9 to 13 there is illustrated a modification of the electrical devices which are controlled by the tool-support feeding mechanism. Instead of having the dog 182 located on the tool slide 31, in this modification the dog, indicated at 182', is secured to the periphery of the handwheel 22" by a set-screw 300. The dog in this case carries a fixed pin 301 having a beveled upper portion which is adapted to contact, at the end of the down feed of the slide 31, with the rounded end of a stem 302. This stem is adjustably mounted in a rocking lever 303, having an extension 303' which is journaled upon a pin 304 carried by two ears 305 which are secured to a bracket 306 carried by the housing 140'. The lever is normally supported for automatic operation in a horizontal plane by a boss 303" thereon (Fig. 11) which rests against the bracket 306. The stem 302 is part of a micrometer and is screw-threaded in a bushing 307 secured in the rocking lever 303, the threads between the bushing and the stem being of a rather coarse character. On the outer left hand end of this bushing there is rotatably mounted a micrometer type thimble 308, having the customary graduation such as the ones marked 0 1 2 7 8 9 which cooperate with the co-axial scribe Y in the upper surface of the bushing 307. The end of the stem fits in a central aperture in the thimble and is pinned to the thimble so that by turning the thimble on the bushing the stem may be adjusted with relation to the beveled pin 301. In order to provide friction so that endwise or axial pressure on this rather coarse pitch mike-screw stem when the dog 182' contacts therewith so that the screw stem will not be backed off, the right-hand end of the bushing is provided with an auxiliary tapered bushing 307'. One side of this auxiliary bushing is split as shown in Fig. 11, whereby as the auxiliary bushing is forced into the bushing 307 it closes in on the stem to frictionally hold it but not to an extent as to preclude its adjustment by rotation of the thimble.

The extension 303' of the rocking lever 303 carries a pin 309 secured therein in any suitable manner and is adapted to cooperate with a plunger 310 associated with a switch which corresponds to the switch 180 previously described. The switch, indicated at 180' is a panel mounted switch supported in the interior of the bracket 306, the wiring of this switch being the same as that previously described and as shown in Fig. 13, the reference characters in Fig. 13 being the same with the addition of the exponent a.

In operation, when the feeding devices for the tool support are operated in the manner before described the hand wheel 22" naturally moves with them so that when the beveled upper side of the pin 301 strikes the rounded end of the stem 302 that end of the lever 303 which carries the stem is rocked upwardly to the position shown by the dot-dash lines 303a in Fig. 11 sufficiently to press the switch plunger 310 in to operate the switch. Further movement of the parts, and it is practically the same movement, brings the end of the dog 182' against the end of the stem 302 to positively arrest further movement of the hand wheel (Fig. 12) and hence

arrest any further movement of the downward feeding movement of the tool slide 31. If the machine is to be operated otherwise than as an automatic down-feed grinder the lever 303 is swung to the dot-dash position indicated at 303b (Fig. 11) which removes the rocking lever 303 out of the path of the dog 182'.

One of the advantages is that a positive stop is provided, by reason of the contact of the dog 182' with pin 301.

Another advantage is that when the grinding wheel must be lowered further as a result of reduction in wheel diameter by wheel wear and truing it is convenient to provide this further lowering by backing off the rounded-end stem 302. (See Fig. 10 in the sectional part.)

The indicia forms a convenient means for properly adjusting the stem with relation to the dog to contact the limit of the down-feed of the tool-support.

Upon the closing of the switch contacts 189a and 226a by the rocking of the lever 303 the spark-out period follows as described in connection with the description of the other form. 25 When the spark-out time is completed, the operation follows the previously described method; that is, the work-table moves to the loading position where it is retained until the re-start manually-operated switch 264 is opened; in such 30 movement, the work-table closes the switch 262 to thereby cause automatic elevation of the tool-holder. The opening of the re-start switch 264 causes the return of the work-table to the working position. Such elevation obviously imparts a partial rotation of the hand wheel 22" in a clock-wise direction (the down-feeding direction being anti-clock-wise) which carries the dog 182' away from the rocking lever 303, allowing this lever to be lowered to its normal position 35 coupled during automatic operation as seen in full lines in Fig. 11. By this operation the spark-out side of the double-throw switch 190' as represented by the contacts 226a and 189a is opened, and the same movement of the contact 189a closing 40 by contact with the contact 101a that side of the switch 190' which is in series with the down-feed switch 180a so automatic down-feeding may be resumed.

Having thus described my invention, I claim:

50 1. In a grinding machine, a reciprocating work-holder, a traveling tool-supporting device, a tool carried by said device, means for feeding said tool-supporting device toward the work on said work-holder, fluid motor-operated means for reciprocating said work-holder, and electrically-operated means automatically retarding the actuation of said motor-operated means in one direction of the reciprocation of said work-holder, an electrical control circuit therefor, a circuit make and break device in said circuit, operated by the travel of the tool-supporting device as it approaches the limit of its range of movement in one direction while the work-holder continues to be moved by said motor-operated means at reduced speed to a loading position beyond its normal range of reciprocation and a delayed action relay in said circuit for temporarily maintaining said electrically operated means in its operative condition subsequent to initiation of 60 return movement of the traveling tool-support.

65 2. In a grinding machine, a reciprocating work-holder, a traveling tool-supporting device, a tool carried by said device, means for feeding said tool-supporting device toward the work on 70 said work-holder, fluid motor-operated means for

75 said work-holder, fluid motor-operated means for

reciprocating said work-holder comprising a cylinder, a fluid-operated piston therein, a fluid circulatory conduit communicating with the cylinder, an electrically operated cut-off valve in the fluid circulatory conduit for reducing the circulation of fluid relative to the cylinder of said fluid motor to retard the operation of said motor operated means in one direction of the reciprocation of said work-holder, while the work-holder continues to be moved by said motor operated means to a loading position beyond its range of reciprocation an electrical control circuit for said cut-off valve, a circuit break and make device therein operated by the travel movement of the tool-supporting device, and a timer member governing the return to normal of the cut-off valve when operated independently of the further travel of the tool supporting device.

3. In a grinding machine, a reciprocatory work-holder, a traveling tool-supporting device, a tool carried by said device, means for feeding said tool-supporting device toward the work on said work-holder, fluid motor-operated means for reciprocating said work-holder, electrically-operated means for retarding the actuation of said motor-operated means in one direction of the reciprocation of said work-holder while the work-holder continues to be moved by said motor-operated means to a loading position beyond its normal range of reciprocation, an electrical control circuit therefor, a make and break device in the circuit operated by the travel motion of the tool-supporting device, and releasable controlled electrical means operated by said work-holder for maintaining said electrically operated means effective to retain said work-holder in loading position after control of said circuit has been removed from the influence of said tool-supporting device.

4. In a grinding machine, a reciprocatory work-holder, a traveling tool-supporting device, a tool carried by said tool-supporting device, electrically controlled fluid actuating means for feeding said device toward the work on said work-holder, means for reciprocating said work-holder comprising a fluid motor, and electrically operated means controlled by said electrically controlled fluid actuating means for feeding said tool-supporting device for preventing reversal of the reciprocatory work-holder by operation of said fluid motor whereby the fluid motor causes the work-holder to continue to move to loading position comprising a blocking valve to block fluid supply to one end of said fluid motor, an electromagnet connected with said valve, means for energizing said magnet actuated by said electrically controlled fluid actuating means for feeding said tool-supporting device after the end of its operation upon the work including a delayed action relay, and manually controlled electrical switch devices closed by said work-holder when moved to loading position for maintaining said magnet energized to retain said work-holder in loading position after the energization thereof has been removed from the control of said tool-supporting device.

5. In a grinding machine, an adjustable tool-support, a reciprocal tool supported thereby, a reciprocatory work-holder, means to impart a feeding movement to said tool-support with relation to said work-holder, means including a fluid motor for reciprocating said work-holder, electrically operated means including an electromagnet for blocking the supply of fluid to one end of the cylinder of said motor to permit said

work-holder to be moved to loading position thereby, a first switch closed by said means to impart a feeding movement to said tool-support at the end of the grinding operation of said tool upon the work, an electrically controlled retractive mechanism energized by the approach of the tool support to the limit of its range of travel for restoring said tool-support to initial position to permit opening of said first switch, a second switch energized by the closing of said first switch, including means to delay the closing thereof to permit a smoothing operation of the tool and adapted to be closed to supply current to said magnet when said first switch is closed, a third switch in series with the second switch, closed by said work-support when moved to its loading position, a fourth switch closed upon the closing of said third switch to maintain said magnet energized after said first and second switches have been opened by the restoring movement of said tool-support, and a fifth switch in series with said fourth switch manually operable to deenergize said magnet to permit said blocking means to return to normal position.

6. In a grinding machine, a reciprocatory work-holder, a fluid operated motor to reciprocate said holder, automatic reversing means for the motor operable by the work-holder as it approaches the limit of a prescribed range of movement in each direction under influence of fluid pressure supplied alternately to opposite ends of the motor, an electrical circuit including an electrically operated device for temporarily arresting the supply of fluid under pressure to one end of the motor while fluid pressure continues to be supplied to the opposite end thereof to continue the operation of the motor and movement of the work-holder in one direction beyond its normal range of reciprocatory movement into a loading position, regardless of the operation of the reversing means, thereby, an adjustable tool-supporting device, means to cause a relative traversing movement between said holder and device, electrically controlled means actuated by said traversing means to feed said tool-supporting device toward the work on said work-holder, electrically controlled means actuated by said electrically-controlled means which feed said tool-supporting device to arrest the feeding movement of said tool-supporting device, and electrically controlled actuating means controlled by said work-holder when moved to loading position to return said tool-supporting device to initial position.

7. In a grinding machine, a reciprocatory work-holder, an adjustable tool-supporting device, a tool carried by said tool-supporting device, electrically controlled fluid actuating means for feeding said device toward the work on said work-holder, means for reciprocating said work-holder comprising a fluid motor, and electrically operated means controlled by said tool-supporting device for blocking the reversal of said fluid motor while the work-holder continues to move beyond its normal range of reciprocation to loading position comprising a blocking valve to block fluid supply to one end of said fluid motor while a supply of fluid under pressure is continued to the opposite end thereof, an electromagnet connected with said valve, means for energizing said magnet actuated by said tool-supporting device after the end of its operation upon the work including a delayed action relay by which the magnet is maintained in energized condition and the blocking valve in operated position regardless of further movement of the tool supporting device,

and manually releasable electrical switch devices closed by said work-holder when moved to loading position for maintaining said magnet energized to retain said work-holder in loading position after the energization thereof has been removed from the influence of said tool-supporting device.

8. In a grinding machine, a reciprocating work-holder, an adjustable tool-supporting device, a tool carried thereby, automatic feeding means for feeding said device toward the work on said work-holder, retracting means therefor, means for reciprocating said work-holder comprising a fluid motor having a cylinder and a movable fluid-operated valve for admitting fluid alternately to each end of the motor cylinder and exhausting it therefrom, means operated by the work-holder for controlling said valve, and electrically operated means controlled by the said automatic feeding means for feeding said tool-supporting device for interrupting the fluid supply by said valve at one end of said motor piston to permit the work-holder to move to a loading position under influence of a fluid supply under pressure to the opposite end thereof, including a rotatable member rotating in unison with the adjustment of the tool-supporting device, a dog carried by said member, an adjustable stem extending into the path of and moved by engagement therewith of said dog and an electric switch operated by said stem for energizing the retracting means for the tool supporting device to restore the tool-supporting device to its starting position.

9. In a grinding machine, a reciprocating work-holder, an adjustable tool-supporting device, automatic means for feeding said device toward the work on said work-holder, means for reciprocating said work-holder comprising a fluid motor cylinder and piston and a movable fluid-operated valve for admitting fluid alternately to each end of said cylinder and exhausting it therefrom, means operated by the work-holder for controlling said valve, and electrically operated means controlled by the said tool-supporting device for controlling said valve to block fluid supply to said fluid motor cylinder at one end of the stroke of said piston while a supply of fluid under pressure is continued to the opposite end of the cylinder to cause said piston to move said work-holder to a loading position, said last-mentioned means comprising a blocking valve in the fluid supply line to block fluid supply therethrough to one end of the cylinder and also including a rotatable member traveling in unison with the feeding movement of the tool-supporting device, a dog carried by said member, an adjustable member extending into the path of said dog as the tool-supporting device approaches the limit of its feeding movement, and an electric switch operated by said adjustable member under influence of the dog to effect retraction of the tool supporting device to its starting position.

10. In a grinding machine, a reciprocating work-holder, an adjustable tool-supporting device, a tool carried by said device, means for feeding said tool-supporting device toward the work on said work-holder including a rotatable member, a dog carried by said member, an adjustable stem cooperating with said dog and an electric switch adapted to be operated by said stem, means for reciprocating said work-holder including a fluid motor having a fluid supply and exhaust means, and electrically-operated means controlled by said means for feeding said tool-supporting device for preventing the reversal of

said motor-operated means by interrupting the supply of fluid under pressure necessary to effect actuation in one direction of the reciprocation of said work-holder while a supply of fluid under pressure is continued thereto to cause the work-holder to be moved in the opposite direction by said motor-operated means to a loading position beyond its normal range of reciprocation, and a valve actuated by the work-holder to progressively restrict the motor exhaust to cushion the movement thereof as said holder approaches loading position.

11. In a grinding machine, a reciprocating work-holder, fluid operated means to reciprocate said holder, electrically controlled means to cause said reciprocating means to move said holder to a loading position an adjustable tool-supporting device, means to cause a relative traversing movement between said holder and device, electrically controlled means actuated by said traversing means to feed said tool-supporting device toward the work on said work-holder means including a rotatable member, operatively connected to and rotated proportionally to the feeding movement of the tool-supporting device, a dog carried by said member, a movable member extending into the path of said dog and engaged and moved thereby as the tool-supporting device approaches the limit of its range of travel said dog and an electric switch adapted to be operated by said movable member controlling the retraction of the tool-supporting device, including, electrically controlled means actuated by said electrically-controlled means which feed said tool-supporting device to arrest the feeding movement of said tool-supporting device, and electrically-controlled actuating means controlled by said work-holder when moved to loading position to return said tool-supporting device to initial position.

12. In a grinding machine, a reciprocating work-holder, means for reciprocating said work-holder through a given range of movement together with means for moving said work-holder to a loading position beyond its normal range of reciprocation, an adjustable tool-supporting device, electrically-controlled means to cause a relative movement between said work-holder and tool-supporting device to bring the same in closer relation after each operation of the tool comprising a rotatable member movable in unison with and proportional to the movement of the tool-supporting device, a dog carried by said member, a switch operating member engaged by said dog as the rotatable member and tool-supporting device reach the limit of their respective ranges of travel, an electric switch operated by said switch operating member, electrically-operated means for prolonging the action of said electrically-controlled means, means controlled by said last mentioned means to cause a relative movement by the work-holder and the tool-supporting device for arresting the feeding action of said device, and electrically-controlled actuating devices controlled by said work-holder when moved to loading position for restoring said tool-supporting device to initial position.

13. A machine tool wherein a vertically and horizontally adjustable tool carrier and a reciprocating work holder are movable relative to each other under influence of hydraulic motive means characterized by an electrical control system therefor including an electrical power circuit, an electrical pilot circuit, time delay relay circuit closers in the pilot circuit retarding opening of the switches in said power circuit, electric

switches in the pilot circuit closed by the approach of the tool holder to the limit of its vertical movement and its horizontal shifting movement respectively, to energize corresponding relays, and electrically energized control elements for the hydraulic motive means in said power circuit operative upon closing of corresponding relays to effect predetermined relative movement of the tool carrier and work holder.

14. A machine tool wherein a tool carrier is vertically and horizontally movable relative to a work holder and the latter reciprocable relative to the tool carrier under influence of separate motive means therefor, characterized by an electrical control system therefor, including an electrical power circuit and an electrical pilot circuit arranged in cooperative relation with the power circuit, intermittently closed circuit make and break devices in the pilot circuit closed by movement of the tool carrier and work holder in predetermined sequence, electrically energized devices in the power circuit, circuit closers in the power circuit energized by closing of the make and break devices in the pilot circuit and delayed action devices in the power circuit for maintaining the power circuit closers closed and the electrically energized devices in the power circuit energized during a predetermined elapsed time period subsequently to the opening of the circuit make and break devices of the pilot circuit, and means for regulating said elapsed time period.

15. A grinding machine wherein a tool carrier is mounted for reciprocation relative to a work piece, through step by step movement in alternate directions, in a vertically adjustable carrier head by adjustment of which the tool is fed toward the work by small increments, including electrically controlled actuating means for advancing the tool carrier head through step by step movement toward the work, an electrical control circuit therefor, including a switch momentarily closed as the reciprocating tool carrier reaches the limit of its range of travel in either direction, a slow action circuit breaker in said circuit closed by the closing of said switch and operative to maintain the circuit closed for a time interval after the opening of the switch to afford sufficient time for the actuating means to advance the tool carrier head.

16. A grinding machine wherein a tool carrier is mounted for reciprocation relative to a work piece, through step by step movement in alternate directions, in a vertically adjustable carrier head by adjustment of which the tool is fed toward the work by small increments, including electrically controlled actuating means for advancing the tool carrier head through step by step movement toward the work, an electrical control circuit therefor, including a switch momentarily closed as the reciprocating tool carrier reaches the limit of its range of travel in either direction, a fluid pressure operated motor for actuating the tool carrier head through successive feeding movements, an electrically actuated valve controlling the alternation of fluid under pressure to said fluid pressure motor to effect alternation thereof, a slow acting circuit breaker in said circuit closed by the momentary closing of said switch and operative to maintain the circuit closed and the electrically operated valve in its operated position for a sufficient time after the opening of the switch for completion of the operation of the tool carrier head adjusting means.

17. A grinding machine wherein a tool carrier is mounted in a vertically adjustable tool carrier

head for reciprocation relative to a work piece, and by adjustment of the tool carrier head the tool is advanced toward the work piece, including a pawl and ratchet mechanism for effecting step by step advancement of the tool carrier head toward the work, a fluid pressure motor for reciprocating the actuating pawl of said pawl and ratchet mechanism, a control valve therefor directing fluid under pressure to said motor for effecting alternating motion of the actuating pawl, electrically energized means for moving the control valve in at least one direction to effect corresponding movement of the actuating pawl, an electrical circuit therefor, a normally open switch in said circuit momentarily closed as the reciprocating tool carrier reaches the limit of its stroke, a delayed action circuit breaker in said circuit closed by the closing of said switch and maintaining the circuit closed and the electrical operating means for the control valve energized throughout a time interval sufficient to complete a feeding movement of the tool carrier head toward the work.

18. A grinding machine wherein a traveling tool carrier is movable relative to a work piece upon a reciprocating work holder, having optionally selective manual and automatic means for adjusting the tool carrier relative thereto, including a manually revoluble rotary shaft operatively connected with the tool carrier, a pair of ratchet wheels upon the shaft, the teeth of which are reversely disposed, a pair of oscillatory actuator arms, one for each ratchet wheel, pawls carried by the arms engageable with the corresponding ratchet wheels, means for independently actuating the oscillatory arms in opposite directions to correspondingly rotate the respective ratchet wheels and the shaft, stops limiting the range of operation of the respective arms to different extent by which one arm is limited to a succession of relative short movement to feed a tool carried by the tool carrier by small increments into operative relation with the work, and the other arm being limited to a relatively greater movement to retract a tool carried by the tool carrier out of operative relation with the work at a greater speed than it is advanced thereto.

19. A grinding machine wherein a traveling tool carrier is movable into and out of operative relation with work upon a work holder, having means for adjusting the tool carrier to move a tool carried thereby into and out of operative relation with the work, including a revoluble shaft, a pair of ratchet wheels carried on the shaft having their ratchet teeth disposed in opposite directions, a pair of actuators one for each wheel, actuating pawls carried thereby for separate operative engagement with the respective ratchet wheels for rotating the respective ratchet wheels and the shaft therewith in alternate directions, motive means for independently operating one of the actuators through successive short steps to advance a tool carried by the tool carrier into operative relation with the work by small increments, and for operating the other actuator through a relatively long step at each operation to thereby retract the tool away from operative relation with the work at increased speed.

20. A grinding machine wherein a traveling tool carrier is movable into and out of operative relation with work upon a work holder, having means for adjusting the tool carrier to move a tool carried thereby into and out of operative relation with the work, including a revoluble shaft, a pair of ratchet wheels carried on the

shaft having their ratchet teeth disposed in opposite directions, a pair of actuators one for each wheel, actuating pawls carried thereby for separate operative engagement with the respective ratchet wheels for rotating the respective ratchet wheels and the shaft therewith in alternate directions, fluid pressure means for actuating the respective actuators separately in opposite directions, means for controlling the operation of the actuators by said fluid pressure means by which one actuator is operated to advance the tool into operative relation with the work through a succession of relatively short steps and the other is operated to retract the tool from operative relation with the work through a relatively long step.

21. A grinding machine wherein a traveling tool carrier is movable into and out of operative relation with work upon a work holder, having means for adjusting the tool carrier to move a tool carried thereby into and out of operative relation with the work, including a revoluble shaft, a pair of ratchet wheels carried on the shaft having their ratchet teeth disposed in opposite directions, a pair of actuators one for each wheel, actuating pawls carried thereby for separate operative engagement with the respective ratchet wheels for rotating the respective ratchet wheels and the shaft therewith in alternate directions, and electrical control means for effecting a succession of relatively short steps of one actuator by which the tool is advanced into operative re-

lation with the work and for effecting a relatively long step of the other actuator by which the tool is retracted from operative relation with the work.

- 5 22. A grinding machine, wherein a reciprocating tool carrier is mounted in a vertically adjustable head for movement toward and from a work piece, including separate actuating mechanisms for raising and lowering the head respectively, independent fluid pressure operated motors for said separate head adjusting mechanisms, stop means for limiting one of said head actuating motors to relatively short range of action whereby the head is advanced toward the work by relatively small increments, the other of said fluid pressure motors being operable through a materially greater range of action whereby the head is retracted away from the work through a relatively long continuous travel movement, electrically controlled valves governing the respective fluid pressure motors, an electrical control circuit, a switch therein momentarily closed as the reciprocating tool carrier reaches the end of its range of travel for energizing the valve of one motor to effect periodic advancement of the head and tool carrier toward the work, and a switch closed as the tool carrier head reaches the end of its range of travel for energizing the valve of the other motor to effect retraction of the tool carrying head.
